UNITED STATES PATENT OFFICE.

FRED W. TOBEY, OF GRAND RAPIDS, MICHIGAN.

METAL RECEPTACLE.

1,427,244.

Specification of Letters Patent. Patented Aug. 29, 1922.

Application filed June 27, 1921. Serial No. 480,810.

To all whom it may concern:

Be it known that I, FRED W. TOBEY, a citizen of the United States, residing at Grand Rapids, county of Kent, State of Michigan, have invented certain new and useful Improvements in Metal Receptacles, of which the following is a specification.

This invention relates to improvements in metal receptacles.

10 The main objects of this invention are:

First, to provide an improved metal receptacle adapted as a waste basket or the like, which is simple and economical in structure, and at the same time very attractive in appearance.

Second, to provide an improved metal receptacle in which the parts may be easily formed and are quickly assembled and finished as desired without the use of soldering 20 or welding or securing means of like character.

Further objects, and objects relating to structural details, will definitely appear from the detailed description to follow.

25 I accomplish the objects of my invention by the devices and means described in the following specification. The invention is clearly defined and pointed out in the claims.

30 A structure which is a preferred embodiment of my invention is clearly illustrated in the accompanying drawing, forming a part of this application, in which;

Figure I is a perspective view of a receptacle adapted for use as a waste basket, 35 embodying features of my invention.

Figure II is a plan view, one corner being partially broken away and sectioned to show structural detail.

40 Figure III is a vertical section on a line corresponding to line 3—3 of Figure II.

Figure IV is a plan view of the blank from which the corner uprights are formed.

Figure V is a plan view of one of the side walls before forming the bottom flange 45 and top bead thereon.

Figure VI is a perspective view of one of the channelled corner irons.

Figure VII is a detail plan view with the corner iron removed.

50 Figure VIII is a detail section on a line corresponding to line 8—8 of Figure II.

In the drawings similar reference characters refer to similar parts throughout the several views, and the sectional views are

taken looking in the direction of the little arrows at the ends of the section lines.

Referring to the drawing, side walls 1 are preferably formed of thin sheet metal provided with inturned flanges 2 at their lower ends, and with out-turned beads 3 at their upper ends. These beads in the structure illustrated are of rectangular cross-sectioned the folding lines for the beads, being indicated at 3, Figure V, and the folding line for the bottom flange being indicated at 4 in the same figure.

The side walls are provided with a series of slots 5 adjacent each vertical edge. The corner uprights 6 are of angled form to embrace the vertical edges of the sidewalls, 70 and are provided with inturned flanges 7, having tongues 8 thereon disposed through the slots 5 of the side walls. These corner uprights are extended below the side walls to provide legs for the receptacle. The bottom 9 fits within the side walls and rests upon their flanges 2. This bottom serves as a locking member for the side walls; that is, it assists in holding them in engagement with the tongues 8 of the corner members. 80

The side walls are further secured by means of the locking strips 10 which are engaged behind the tongues 8, the locking strips being engaged behind the tongue by a longitudinal sliding movement. The tongues are 85 preferably folded upon the locking strips as shown in Figs. II and III. The locking strips hold the side walls upon the tongues of the corner members, and also hold the bottom in place. The channelled corner irons 11 are engaged over or embrace the upper ends of the corner uprights and the locking strips, and are provided with extensions 12 which are clamped under the beads of adjacent side walls, thereby locking all 90 of the parts securely in position, it being impossible to disassemble them without removing these corner irons.

When the tongues are clamped down upon the locking strips the parts are all rigidly 100 supported. By leading the upper edges of the side walls, and providing the flanges 7 on the corner members an appearance of massiveness is secured.

My improved receptacle is simple and economical in its parts, the side walls, corner uprights, locking strips and corner caps being duplicates. The parts are easily as-

sembled, and when assembled the structure is very strong and durable and at the same time is attractive and finished in appearance.

Having thus described my invention what 5 I claim as new and desire to secure by Letters Patent, is:

1. In a receptacle, the combination of the side walls provided with inturned flanges at their lower edges and with outwardly projecting beads at their upper edges, said side walls having a series of slots adjacent their vertical edges, angled corner uprights having inturned flanges on their vertical edges provided with the tongues engaging the slots 15 of said side walls, a bottom resting on the bottom flanges of said side walls, bottom and side wall locking strips disposed behind said tongues to retain the side walls thereon, the tongues being folded upon said strips, and 20 channelled corner irons embracing the upper ends of said corner uprights and locking strips and clamped upon the beads of adjacent side walls.

2. In a receptacle, the combination of the side walls having a series of slots adjacent their vertical edges, angled corner uprights having inturned flanges on their vertical edges provided with tongues engaging the slots of said side walls, wall locking and 25 bracing strips disposed diagonally of the corners with their edges behind said tongues bracing the side walls and retaining them in engagement with said tongues, and channelled corner irons embracing the upper 30 ends of said corner uprights and locking strips and secured to adjacent side walls.

3. In a receptacle, the combination of the side walls provided with inturned flanges at their lower edges and having a series of 40 slots adjacent their vertical edges, corner uprights embracing the vertical edges of the side walls and provided with tongues engaging the slots thereof, a bottom resting on the bottom flange of said side walls, locking and bracing strips disposed diagonally of the corners with their edges behind 45 said tongues bracing the side walls and retaining them in engagement with said tongues, and corner irons engaging the upper ends of said corner uprights and locking strips clamping said locking strips upon said bottom and clamped upon the beads of adjacent side walls.

4. In a receptacle, the combination of the side walls having a series of slots adjacent their vertical edges, corner uprights embracing the vertical edges of the side walls and provided with tongues engaging the

slots thereof, locking and bracing strips disposed diagonally of the corners with their edges behind said tongues bracing the side walls and retaining them in engagement with said tongues, and corner irons engaging the upper ends of said corner uprights and locking strips clamping said locking strips upon said bottom and secured to adjacent side walls.

5. In a receptacle, the combination of the side wall provided with inturned flanges at their lower edges and having a series of 65 slots adjacent their vertical edges, corner uprights embracing the vertical edges of the side walls and provided with tongues engaging the slots thereof, a bottom resting on the bottom flanges of said side walls, and a locking member coacting with said tongues to retain the side thereon and brace the side walls and clamp the bottom upon said flanges.

6. In a receptacle, the combination of the 70 side walls having slots adjacent their vertical edges, corner members provided with tongues engaging the slots of adjacent side walls, a bottom supported by said side walls, locking and bracing strips engaged behind 75 said tongues bracing the side walls and retaining them in engagement with said tongues holding the bottom in position, and corner cap members engaging the upper 80 ends of said corner uprights and locking strips and secured to adjacent side walls.

7. In a metal receptacle, the combination of the side walls having slots adjacent their vertical edges, corner members provided with tongues engaging the slots of adjacent 85 side walls, a bottom supported by said side walls and locking strips engaged behind said tongues to retain the side walls thereon and hold the bottom in position, the tongues being clamped upon said strips.

8. In a metal receptacle, the combination of the side walls having slots adjacent their vertical edges, corner members provided with tongues engaging the slots of adjacent 90 side walls, a bottom supported by said side walls, and locking and bracing strips engaged behind said tongues to retain the side walls thereon and hold the bottom in position.

In witness whereof, I have hereunto set 110 my hand and seal in the presence of two witnesses.

FRED W. TOBEY. [L.S.]
